UNITED STATES PATENT OFFICE.

EDWARD J. KING AND THOMAS R. KENNEDY, OF ROCHESTER, NEW YORK, ASSIGNORS TO THE CO-OPERATIVE FOUNDRY COMPANY, OF SAME PLACE.

DESIGN FOR A COOKING STOVE OR RANGE.

SPECIFICATION forming part of Design No. 27,043, dated May 11, 1897.

Application filed January 4, 1897 Serial No. 617,986. Term of patent 7 years.

To all whom it may concern:

Be it known that we, EDWARD J. KING and THOMAS R. KENNEDY, citizens of the United States, and residents of the city of Rochester, in the county of Monroe and State of New York, have invented and produced a new and original Design for Cooking Stoves and Ranges, of which the following is a specification, reference being had to the accompanying drawings, in which—

Figure 1 is a perspective view of a stove or range, showing our design. Fig. 2 is an end view thereof, showing also the details of ornamentation of a teakettle-shelf and of an oven-shelf.

The leading features of our design are found in the parts hereinafter particularly specified, and pointed out in the claims. The general design of the whole stove is of rococo pattern, involving conventionalized leaf-like and scroll ornamentations.

The base ornamentation 1 of the stove is a band, involving panels 2. These panels have scroll borders 3, including a row of looped and curled ornaments. Within certain of the panels 2 there is also a reticulated portion, and the panels are joined by leaf-like scroll ornaments 5. The legs 6 have ornamentation of a similar character, including a border 7 and a central rib 8. The legs are plain at the lower portion, but have the scroll and leaf-like ornamentation on a convex surface on the upper parts thereof. Above this base portion 1 is the main stove portion, which has the ornamented oven-door 9, provided in the middle with a smooth slightly-convex portion 10, on each side of which are scroll and leaf-like ornaments 11, and on the side and lower edges are the ribs 11'. In the center of the door is the escutcheon 10', having in the center a slightly irregular Maltese cross surrounded by scrolls and leaf-like ornaments, and having in the upper and lower parts a name-plate, as shown.

The reservoir-panel 12 has similar leaf-scroll ornamentation 13, an irregularly fluted and scrolled border 14, and a reticulated panel 15.

The fire-pot door 16 has similar scroll-leaf ornamentation and a central panel 17, which is plain. Below the fire-pot door 16 is a panel

18, and which has similar scroll and leaf-like 50 ornamentation 19.

20 is the hearth, which in the present instance is plain. Underneath the hearth is the ash-pit section, with inclined sides, having thereon the vertical flutings 21 and the 55 scroll ornamentation 22, together with a plain portion 23 on the front.

Underneath the oven-door and above the base 1 is the oven-shelf 24, having plain edges and scrolled ornamentation 25 upon its upper 60 surface.

26 is the end ash-pit door, which is convex and is provided with rounded edges. The ornamentation 27 in the upper part of this door is symmetrical with reference to a middle vertical line, and consists of the scrolled ornamentation harmonious with that heretofore referred to. In the lower part of this door are a series of parallel oblong openings 28, having between and about them small ornaments 29, similar in character to the ornamentation in the upper part.

Above the door 27 is the feed-door 30, having a series of parallel vertically-arranged ovoid openings 31, and between and about 75 said openings are scrolled leaf-like ornaments 32, similar to those hereinbefore described.

The stove-top has a smooth border 33, having an upper rounded edge.

Above the top of the stove is the central 80 convex flaring smoke-pipe or flue section 34, having thereupon an irregular Maltese cross 35, surrounded by scrolls 36 and conventionalized leaves 37. On either side of the central section are the side supporters 38, 85 consisting of open-work scrolls 39 and an open-work reticulated portion 40. Along the lower edges of the supporters 38 and of the central panel 34 is a beaded edging 41.

Above the smoke-pipe section 34 is a smooth 90 edging 42, sharply defined on its lower side and rounded on its upper side. Above this is the hot closet, having the front panels or doors 43, provided with symmetrically-arranged leaf and scroll like ornamentation 44 95 on each end, a smooth slightly convex portion 45. A name-plate or escutcheon 46 is applied on said smooth portion 45 of the hot-

closet doors, having the ornamental monogram "I. R. C." thereon upon a background of scroll and leaf like ornamentation. The hot closet has end panels 47, having a border of the same scrolled-leaf ornamentation 48, together with a central reticulated portion. The top of the hot closet has a smooth edge 51, like the smooth edging above described.

Above the hot closet is an ornamental top or cornice plate 52, composed of scrolls and openings therethrough, a central portion somewhat higher than the end portions, and with an irregular contour composed of different convex and concave curves.

15 Upon each side bracket 38 is a horizontal "teakettle-shelf" 53, irregularly oval in contour and having upon its surface scrolls and beaded fan-like ornamentation 54.

What we claim is—

20 1. In a design for a stove, or range, the design for the leg, substantially as herein shown and described.

2. In a design for a stove or range, the design for the base portion, substantially as 25 herein shown and described.

3. In a design for a stove or range, the design for the lower portion, comprising the base 1 and the legs 6, substantially as herein shown and described.

30 4. In a design for a stove or range, the design for the reservoir-panel, substantially as herein shown and described.

5. In a design for a stove or range, the design for oven-door, substantially as herein 35 shown and described.

6. In a design for a stove or range, the design for the escutcheon for the oven-door, substantially as herein shown and described.

7. In a design for a stove or range, the 40 design for the oven-shelf, substantially as herein shown and described.

8. In a design for a stove or range, the design for the fire-pot door, substantially as herein shown and described.

9. In a design for a stove or range, the design for the panel 18 below the fire-pot door, substantially as herein shown and described.

10. In a design for a stove or range, the design for the ash-pit, substantially as herein shown and described.

11. In a design for a stove or range, the design for the end ash-pit door, substantially as herein shown and described.

12. In a design for a stove or range, the design for the feed-door, substantially as herein shown and described.

13. In a design for a stove or range, the design for the smoke pipe or flue, substantially as herein shown and described.

14. In a design for a stove or range, the design for the side bracket for the smoke pipe or flue, substantially as herein shown and described.

15. In a design for a stove or range, the design for a front panel or door of the hot 65 closet, substantially as herein shown and described.

16. In a design for a stove or range, the design for the escutcheon for the door of the hot closet, substantially as herein shown and de- 7c

scribed.

17. In a design for a stove or range, the design for the end panel of the hot closet, substantially as herein shown and described.

18. In a design for a stove or range, the de- 75

sign for the top or cornice plate, substantially as herein shown and described.

19. In a design for a stove or range, the de- 80

sign for the teakettle-shelf, substantially as herein shown and described.

20. The design for the stove or range, sub- 80

stantially as herein shown and described.

EDWARD J. KING.
THOMAS R. KENNEDY.
